UNITED STATES PATENT OFFICE.

CHARLES H. BELLAMY, OF PHILADELPHIA, PENNSYLVANIA, ASSIGNOR, BY DIRECT AND MESNE ASSIGNMENTS, TO CONCRETE & CLAY PRODUCTS COMPANY, A CORPORATION OF DELAWARE.

ORNAMENTAL TILE.

982,029.

Specification of Letters Patent.

Patented Jan. 17, 1911.

Application filed April 9, 1909. Serial No. 488,795.

To all whom it may concern:

Be it known that I, CHARLES H. BELLAMY, a British subject, and resident of Philadelphia, in the county of Philadelphia and 5 State of Pennsylvania, have invented certain new and useful Improvements in Ornamental Tiles, of which the following is a full, clear, and exact description.

This invention relates to the manufacture 10 of tiles in which the faces thereof present a marbled or mottled appearance as constituted by the production thereof of separate portions or pieces of plastic material of different colors combined in a particular 15 manner and formed and solidified by molding and compression.

The tile such as above referred to is preferably made with a back or body of a low 20 grade cement or other suitable plastic material which is much cheaper than the materials which are combined to produce the variegated, marbled or mottled face.

Another object is to embody in the tile 25 thin strips of metal, the extremities of which protrude beyond the edges of the tile and constitute means for the fastening of the same on a floor or wall; and in the provision of the sheet metal fastening strips they have a peculiar arrangement relatively 30 to the length of the tile edges so that when the tiles are matched together the extremities of the strips of any given tile may underlie the next tile and be non-coincident or offside from the fastening strip of the 35 adjacent tile.

The invention is rendered apparent in and by the following description in conjunction with the accompanying drawings, and is defined in the claims.

40 In the drawings:—Figure 1 is a plan view of a tile showing a face thereof such as might be produced under the exercise of this invention; Fig. 2 is a perspective view to indicate a manner of arranging the separate differently colored plastic materials preparatory to a molding and compressing thereof to make the tile face; Fig. 3 is a sectional view showing the tile face constituting plastics and the material for making the tile back in a press mold preparatory to receiving the compression; Fig. 4 is a similar view to Fig. 3 but indicating the parts as in their conditions after having received the compression. Fig. 5 is a sectional view 45 through one of the completed tiles. Fig. 6

is a plan view showing two of the tiles in matched relations and indicating the relative dispositions of the edgewise extending fastening members. Fig. 7 is an illustration to indicate the somewhat different one of 60 the many forms of variegated tile face which may be produced in accordance with this invention.

I will now describe the mode of producing the tile in accordance with this invention 65 so that the characteristic of the tile itself will be fully apparent.

In the drawings, Figs. 2 and 3, *a a* represent separate portions of plastic material of a given color, such, for instance, as red; and *b b* represent separate portions of plastic material of another color, such, for instance, as blue. As indicated in the views referred to, the materials *a* and *b* are produced in the form of comparatively narrow 70 strips as may practicably be done by rolling out the colored cement into sheets and cutting the same into strips. The strips *a* and *b* are laid in criss cross arrangement and are superimposed upon (or may be overlaid by) 75 a sheet or layer *c* of a plastic cement which may be of another color, such, for instance, as white. The crossing separated strips *a* and *b* of the different colors are placed in the bottom of an upwardly open press mold 80 *D*—the molding chamber which is square or of such other form corresponding to the tile to be produced,—and the layer *c* lies over and upon the open-work mat of plastic material constituted by the criss-cross strips. 85 *a* and *b*.

Usually and preferably, previous to the compression of the portions *a*, *b* and *c* of the differently colored plastic materials in the press mold, a suitable quantity of plastic material of low grade or cheaper quality is provided in the press mold, as indicated at *d*, for the production of the tile body or back; and when the powerful pressure is exerted on the materials in the press mold by the plunger *E*, the materials *d*, *c*, *b* and *a* become compressed, solidified and connected, the separated strips *b b* transversely overlying the separated strips *a* in the press mold are forced down to plane with the portions *a* and more or less of the plastic compound comprised in the layer *c* is downwardly displaced into the interstices between the edges of the strips *a*; and thus a tile is produced 100 having a solid face constituted by the vari- 105 110

ously colored plastic compounds, portions of all of which are visible in more or less irregular distribution and contour at the face of the tile.

5 In Fig. 7, a tile is represented such as would be produced,—entirely consistent with this invention,—by depositing pieces a^2 , a^2 , of comminuted plastic material of one color (for instance, red) in the bottom of the 10 press mold, commingled with comminuted plastic material b^2 of another color, for instance, blue,—these commingled, separated portions of the plastic material being superimposed by the sheet or layer c^2 of the still 15 different color,—it being understood that the compression to which the materials are subjected as before described cause a flattening and plane facing of the interspersed plastic portions a^2 and b^2 and a displacement in all 20 spaces between the portions a^2 and b^2 of so much of the layer c^2 as to make the face stratum of the tile solid and with its continuous surfaced face a mottling or variegation of the colors, for instance, red, white and 25 blue, of the portions a^2 , b^2 , and c^2 . The plastic tile has one or more sheet metal strips g embedded within its body with their extremities extending edgewise beyond the tile at the corner or edge thereof adjoining the 30 back. As shown, these strips are arranged in pairs which cross each other, those of each pair being in parallelism, and in lines oblique to the edges of the tile so that as the extremity of each strip is regarded relatively 35 to that of another strip at the same edge of the tile the one extremity is nearer the one corner than is the extremity of the other strip to the other corner of the tile as clearly perceived on an inspection of Fig. 6, where- 40 by in the setting up or fastening of one tile on a floor or wall edgewise adjoining another, the attachment means for one tile would be out of line with the corresponding attachment means of the adjoining tile. The 45 metallic strips g are provided of bowed form, as represented in Figs. 3 and 4, so as to be by the greater portion of their length comparatively deeply embedded in the tile back while their extremities emerge and ex- 50 tend outwardly from the tile body about coincident with the corners of the tile at the rear face thereof.

After the tiles have been made and allowed to harden, the extremities of the metallic strip are slightly bent from the position which they have at the time of the making of the tile, represented in Fig. 4, to the

position shown in Fig. 5, in which the outwardly extending fastening members are exactly, or approximately, coincident with the plane of the rear face of the tile. 60

This invention is susceptible of a wide latitude of change as regards the formation and initial arrangement of the separated portions of plastic materials which constitute the facing of the tile, the number of different colors which the separate plastic portions may have, and the selection of colors. 65

I claim:

1. A tile having a continuously flat face, of the character described, constituted in part by portions of plastic material of different colors, and in separated relations whereby interstices are provided between them, and in part by a sheet or layer of plastic material of still another color than the first 75 named portion, said separate portions and sheet of plastic material being united with parts of the sheet or layer disposed in the interstices between the separate plastic portions, and all conformed at their exterior to 80 a continuous flat surface, and a backing of inferior plastic material molded to and connected with the variably colored face portion.

2. A tile having a face of the character described, said face being constituted by series of strips of differently colored plastic material arranged in separated and crossed relations and having a layer or sheet of a plastic material of a still different color next 90 within the separated crossed and variably colored strips, said layer and cross strips being compressed and rendered solid and united with portions of said layer disposed within and visible through the interstices 95 between the crossing strips, and a backing for the tile of inferior plastic material molded to and connected with the variably colored face portion of the tile by molding and compression. 100

3. A tile having pairs of metallic strips embedded diagonally therein with their extremities protruding beyond the edge of the tile, the extremity of one strip at a given edge of the tile being nearer one corner of 105 the tile than the extremity of the other strip as related to the other corner of the tile.

Signed by me at Philadelphia, Pa., in presence of two subscribing witnesses.

CHARLES H. BELLAMY.
